US0D1054309S

(12) United States Design Patent (10) Patent No.: US D1,054,309 S
(45) Date of Patent: * Dec. 17, 2024

(54) WRISTBAND

(71) Applicant: Music Academy Success, LLC, Irmo, SC (US)

(72) Inventor: Thomas M. Fort, Jr., Irmo, SC (US)

(73) Assignee: Music Academy Success, LLC, Irmo, SC (US)

() Term: 15 Years

(21) Appl. No.: 29/824,125

(22) Filed: Jan. 21, 2022

(57) CLAIM

The ornamental design for a wristband, as shown and described.

DESCRIPTION

FIG. 1 is a perspective view of a wristband according to the invention;

FIG. 2 is a front elevation thereof;

FIG. 3 is a rear elevation thereof;

FIG. 4 is a top plan view thereof; and,

FIG. 5 is a bottom plan view thereof.

The broken lines shown in the drawings illustrate portions of the article and form no part of the claimed design.
